SEWING MACHINE NEEDLE

Omer J. Rainville, South Attleboro, Mass., assignor to E. Z. I. Needle Company Incorporated, Providence, R. I.

Application April 30, 1940, Serial No. 332,552

2 Claims. (Cl. 112—224)

This invention relates to certain new and useful improvements in sewing machine needles.

The needle disclosed herein comprises a main body portion including a shank, a hub with a tapered neck connecting the shank to the hub with a resilient thread guide arm attached to the shank of the needle to facilitate threading thereof and a machine for attaching the resilient thread guide arm to the shank of the needle is illustrated in application for patent filed by Omer J. Rainville on June 17, 1940, Serial No. 341,051.

The primary object of this invention is to provide a sewing machine needle comprising a shank pointed at one end with a mounting hub at the other end of the shank connected thereto by means of a tapered neck with one side of the neck concaved and with a resilient thread guide arm anchored at its outer end to the needle shank adjacent the pointed end in proximity of the eye of the needle with the inner end of the resilient arm overlying the concaved portion of the neck to facilitate the placement of a thread between the resilient arm and shank of the needle for movement longitudinally of the needle shank to the eye portion thereof.

It is a further object of the invention to provide a sewing machine needle of the foregoing character wherein the shank of the needle is longitudinally cut away at one side to provide an upstanding longitudinally extending rib with its side edges spaced inwardly of opposite sides of the needle shank to provide thread guide grooves, the needle shank and rib gradually widening from a point substantially midway the ends thereof toward the hub for strengthening the needle shank out of the zone where the pointed threaded end of the needle passes through materials being sewed.

With the above and other objects in view that will become apparent as the nature of the invention is better understood, the same consists in general of certain novel details of construction and combination of parts hereinafter more fully described, illustrated in the accompanying drawings and claimed.

In the accompanying drawing:

Figure 1 is a side elevational view of the needle blank before the resilient thread guide arm is attached thereto.

Figure 2 is a top plan view of the needle blank shown in Figure 1 and illustrating the cut-away portion at one side of the needle shank defining a longitudinally extending rib.

Figure 3 is a cross-sectional view taken on line 3—3 of Figure 1 adjacent the outer end of the

needle blank, showing the relatively narrow rib carried by the shank of the needle blank.

Figure 4 is a cross-sectional view taken on line 4—4 of Figure 1, showing the rib of increased width adjacent the supporting hub for the needle.

Figure 5 is a cross-sectional view taken on line 5—5 of Figure 1 through the tapering neck connecting the needle shank to the supporting hub,

10 Figure 6 is a cross sectional view taken on line 6—6 of Figure 2,

Figure 7 is a side elevational view of the completed sewing machine needle with the resilient thread guide arm attached thereto and having 15 the inner end of the thread guide arm cooperating with the tapered neck connecting the needle shank to the supporting hub to facilitate threading of the needle.

Figure 8 is a top plan view of the completed 20 needle shown in Figure 7, and

Figure 9 is a cross-sectional view taken on line 9—9 of Figure 7.

The needle blank as shown in Figures 1 to 6 comprises a shank designated in general by the 25 reference character 10, the inner end of the shank carrying the usual enlarged supporting hub 11 and being connected thereto by the tapering or conical neck 12. As clearly shown in Figure 2, the shank 10 of the needle gradually increases in diameter from a point substantially midway the ends thereof to the conical neck 12 as shown at 10^a, the outer needle shank point 10 being of standard diameter common to sewing machine needles while the section 10^a of increased cross-sectional area is spaced from the zone of sewing operations and increases the strength of the needle.

One side of the needle shank 10 is longitudinally cut away on a chordal line 13 between the 40 point 14 at the end 15 of the shank 10 in which the thread eye is formed and the adjacent end 16 of the conical neck 12 and rising from said cut-away portion 13 and centrally thereof is an upstanding rib 17 spaced from opposite sides of 45 the needle shank 10 as illustrated in Figure 2, said rib 17 providing opposite thread guide grooves 18. The narrowest portion of the rib 17 is disposed outwardly of the outer end of the widened portion 10^a of the needle shank and 50 said rib 17 as shown at 17^a in Figures 2 and 4 gradually widens along the gradually widened section 10^a of the needle shank and further acts to strengthen the needle.

The outer end 17^b of the rib 17 terminates 55 in spaced relation to the outer end 15 of the

needle shank 10 and the cut-away side portion 13 of the needle shank outwardly of said rib 17 is provided with a second upstanding rib 19 of tapering formation in plan view as illustrated in Figure 2 with the smaller end 19a of the rib 19 terminating in spaced relation to the outer end 17b of the rib 17 to provide a cross opening 20 to constitute the eye of the needle.

A resilient thread guide arm 21 shown in Figures 7 to 9 overlies the cut-away side portion 13 of the needle shank and is transversely proportioned relative to the needle shank to provide a complete circular structure in cooperation therewith as shown in Figure 9, the outer end of the resilient arm 21 being spot-welded or otherwise secured as at the point 22 to the upper face of the rib 19 outwardly of the needle eye 20, the resilient arm lying in flat engagement with the rib 17 and its widened portion 17a.

As shown more clearly in Figures 7 and 8, the inner end 23 of the resilient arm 21 extends over a portion of the conical neck 12 and as shown in Figures 1, 5, 7 and 8 that side of the conical neck 12 in line with the cut-away portion 13 is concaved as at 24 to provide a pocket 25 between the concaved wall 24 and the adjacent overlying end 23 of the resilient arm to facilitate the placement of a thread for movement between the rib 17 of the needle shank and the resilient arm 21 to the needle eye 20. In the mounting of the resilient arm upon the needle shank, the outer end 15 of the shank is fashioned into the usual sharpened point 15a shown in Figures 7 and 8.

From the above detailed description of the invention, it is believed that the construction and operation thereof will at once be apparent, and while there is herein shown and described the preferred embodiment thereof, it is to be understood that minor changes may be made in the details of construction, such as will fall within the scope of the invention as claimed.

I claim:

1. In a sewing machine needle of the character described, a needle shank having an eye adjacent its outer end, a mounting hub, a tapering neck connecting the shank to the mounting hub,

one side of the shank being cut away to provide a longitudinally extending rib terminating at one end adjacent the neck and defining lateral thread guide grooves, and a resilient arm anchored at its outer end to the outer end of the shank in overlying relation to said rib with the inner end of the resilient arm overlapping the outer end only of the tapering neck with the inner terminal end spaced laterally of the tapering neck and providing an unobstructed opening to facilitate placement of a thread between the resilient arm and shank rib for movement into the eye of the needle, said shank being of constant diameter from a point substantially midway the ends thereof to the eye at the outer end and the inner end of the shank from the portion of constant diameter to the outer end of said tapering neck being of gradually increasing diameter inwardly to strengthen the needle shank.

2. In a sewing machine needle of the character described, a needle shank having an eye adjacent its outer end, a mounting hub, a tapering neck connecting the shank to the mounting hub, one side of the shank being cut away to provide a longitudinally extending rib terminating at one end adjacent the neck and defining lateral thread guide grooves, and a resilient arm anchored at its outer end to the outer end of the shank in overlying relation to said rib with the inner end of the resilient arm overlapping the outer end only of the tapering neck with the inner terminal end spaced laterally of the tapering neck and providing an unobstructed opening to facilitate placement of a thread between the resilient arm and shank rib for movement into the eye of the needle, said shank being of constant diameter from a point substantially midway the ends thereof to the eye at the outer end and the inner end of the shank from the portion of constant diameter to the outer end of said tapering neck being of gradually increasing diameter inwardly to strengthen the needle shank, and said rib being of gradually increasing width corresponding to the diametrically increased portion of said shank.

OMER J. RAINVILLE.
